UNITED STATES PATENT OFFICE.

DAVID F. VAUGHAN, OF RIVERTON, AND CHARLES Z. VAUGHAN, OF HADDONFIELD,
NEW JERSEY.

ANTICREEPER FOR RAILROAD-RAILS.

1,180,889.

Specification of Letters Patent. Patented Apr. 25, 1916.

Application filed July 31, 1914. Serial No. 854,249.

To all whom it may concern:

Be it known that we, DAVID F. VAUGHAN, citizen of the United States, residing at Riverton, county of Burlington, State of New Jersey, and CHARLES Z. VAUGHAN, citizen of the United States, residing at Haddonfield, county of Camden, State of New Jersey, have invented certain new and useful Improvements in Anticreepers for Railroad-10 Rails, of which the following is a specification.

Our invention relates to anticreepers for railroad rails and particularly to anticreepers of the type wherein a bar adapted to extend beneath a rail base and having means to engage the same is employed in conjunction with a part adapted to coöperate with the bar to clamp the anticreeper to the rail.

The object of our invention is to provide an anticreeper of this type and of novel, simple and efficient construction having provision, first, whereby one element of the anticreeper may be sprung from a normal condition and caused to clamp the anticreeper to the rail intending to resume said normal condition; secondly, whereby the part coöoperating with the bar may be made in the form of a wedge constructed and related to the bar in a manner to have a three point bearing and to increase the strength of the bar in such constructions; thirdly, whereby a wedge may be employed between the rail and an element adapted to engage the rail and held in place by spring pressure and provided with means to prevent movement of the said element toward the small end of the wedge, or to prevent the said element and the wedge from being pulled apart; and, fourthly, whereby various novel and advantageous results are attained; all as will be hereinafter fully described and claimed.

In the accompanying drawings, illustrating our invention: Figure 1 is a plan of a portion of a railroad rail, a portion of a cross tie and one form of our improved anticreeper applied to the rail. Fig. 2 is a section on line 2-2 of Fig. 1. Fig. 3 is a side view of the parts shown in Fig. 1. Fig. 4 is a plan view of a modified form of the wedge member. Fig. 5 is a side view of the wedge member shown in Fig. 4. Fig. 6 is an end view of the wedge member shown in Figs. 4 and 5.

Referring to the drawings, 1 designates a

portion of a railroad cross tie and 3 a railroad rail of usual construction. The cross tie 1 forms a stationary part of the road bed which supports the rail 3 and over which the rail tends to creep under the well known conditions.

Our anticreeper is applied to the base 4 of the rail 3 and is constructed as follows:

Extending transversely beneath the rail 3 is a bar 5 having a rail gripping part of hook 6 formed on one end thereof which extends over one side of the rail base 4. The other end of the bar 5 also has a hook 7 formed thereon, comprising an upwardly-extending portion 8 spaced from the adjacent side of the rail base 4, and an inwardly-extending portion 9 extending over the adjacent side of the rail base 4. The distance between the portion 8 and rail gripping hook 6 is such that the rail base 4 may pass between the portion 8 and hook 6 after the portion 9 has been first placed over one side of the rail base, in applying the bar 5 to the rail from the bottom thereof. After thus applying the bar to the rail, the bar is adjusted so that the hook 6 and portion 9 thereof rest upon the top of the rail base 4, as shown.

Arranged between the bar 5 and the rail base 4, and preferably between the top of the bar and the bottom of the rail base is a part or member 10 which is formed of spring metal and which, in the present embodiment of our invention, constitutes the stop part of the anticreeper adapted to engage the cross tie 1 to prevent the rail from creeping. This member 10 comprises a vertical portion 11 adjacent to the cross tie 1 and a rearwardly extending portion 12 formed integral with the vertical portion 11. The portion 12 extends between the bar 5 and the rail base 4 and is made concavo-convex in cross section, providing three separate bearing faces 16, 17 and 18. The two lower bearing faces 16 and 17 are spaced apart transversely of the rail 3 and bear upon the top of the bar 5; and the upper bearing face 18 bears against the bottom of the rail 3 above the space between the two bearing faces 16 and 17, thus providing a three point bearing for the portion 12. In the normal condition of the portion 12, the distance between the top of the bar 5 or a line drawn between the two bearing faces 16 and 17 and

the bearing face 18 is greater than that shown in the drawings, the concavo-convex portion 18 having been sprung from its normal condition to bring the two bearing faces 16 and 17 closer to the bottom of the rail 3, thereby firmly clamping the anticreeper to the rail in tending to resume said normal condition. The upper bearing face 18 of the portion 12 extends parallel to the bottom 5 of the rail 3 longitudinally of the portion 12 and the lower bearing faces 16 and 17 are inclined rearwardly and upwardly from the portion 11, so that the portion 12 constitutes a wedge extending between the bar 5 and rail 3 and having its large end spaced from the bar 5 and adjacent to the cross tie 1, so that should the rail 3 tend to creep forwardly or in the direction of the arrow, the rail will tend to carry the bar 5 with it toward the large end of the wedge and thus cause the anticreeper to increase its grip upon the rail.

By engaging the part or member 10 with the bar 5 at the spaced points 16 and 17 located on the respective sides of the center of the bar we are enabled to employ a much lighter bar than if the part or member 10 had a bearing upon the central portion of the bar 5 which would bend it downwardly under much less pressure than would be required to bend it down with the bearing points arranged according to our invention.

The advantages of the three point bearing of the portion 12 of the member 10 is the same whether the portion 12 be rigid or formed of spring metal; and we may here remark that either the bar 5 or the wedge 12 of the member 10 may be formed of spring metal and act as a spring to clamp the anticreeper to the rail, while the other remains rigid, or both of them may be formed of spring metal and clamp the anticreeper to the rail by their combined spring action. We prefer, however, to make the bar 5 rigid and have the spring action present only in the wedge portion of the member 10. When it is desired to have the bar 5 act as a spring it will be constructed of suitable metal and be sprung downwardly between the ends thereof by the wedge portion 12 of the member 10 and will thereafter firmly clamp the anticreeper to the rail in tending to resume its normal condition.

The sides of the wedge portion 12 of the member 10 are provided with stop projections 14 which are cut from the body of the portion 12 and bent to extend downwardly therefrom, as clearly shown in the drawings. These projections 14 are adapted to prevent accidental movement of the bar 5 toward the small end of the wedge from different positions when the bar 5 is engaged with the portion 12; and the bottoms or sides of the projections 14 toward the small end of the wedge are inclined or beveled, as shown, to

permit the bar 5 to pass them when the bar is moved toward the large end of the wedge in applying the anticreeper to the rail.

The operation of applying the anticreeper to the rail is as follows: The member or stop part 10 is placed beneath the rail 3 adjacent to the cross tie 1 and against the bottom of the rail base 4, and the bar is then placed transversely beneath the rail, and its hooked end portions are passed over the sides of the rail base 4 into the position shown, but rearwardly of the member 10. The bar 5 is then driven forwardly or toward the cross tie 1 by any suitable means. As the bar 5 is thus driven forwardly, it passes beneath the wedge portion 12 and engages the bearing faces 16 and 17 and springs the sides of the portion 12 toward the bottom of the rail 3, and the farther the bar 5 is driven toward the cross tie 1, the greater will be the spring action of the wedge in firmly clamping the anticreeper to the rail. When the bar 5 is driven forwardly, the wedge 12 or the projections 14 or both spring toward the rail 3 to permit the bar to pass the projections which thereafter spring back rearwardly of the bar and prevent it from being accidentally shifted rearwardly or toward the small end of the wedge. It will be observed that the projections 14 on the respective sides of the wedge portion 12 are arranged in staggered relation to each other thereby increasing the number of positions from which rearward displacement of the bar will be prevented for a given number of projections.

The employment of the stop projections 14 is an important feature of our invention because heretofore a serious objection to anticreepers of the type involving the use of a wedge, as herein described, has been that when the stop part designed to bear against the stationary part of the road bed, such as a cross tie, becomes frozen in the ballast, any retrograde movement of the rail, such as will frequently occur, on account of temperature changes, will draw the bar backward on the wedge and thus loosen it.

In the construction of the part or wedge member shown in Figs. 4, 5 and 6, the projections 14 are omitted and the spaced lower bearing faces 16 and 17 extend parallel to each other.

We claim:

1. The combination with a railroad rail having a base, and a stationary part of a road bed, of an anticreeper comprising a bar extending beneath the rail and provided with means to engage the top of the rail base on each side thereof, and a stop part adapted to engage said stationary part and having a wedge extending between the bottom of the rail and the top of the bar, said wedge having three separate bearing faces

two of which are spaced apart transversely of the rail and bear upon the bar and the other of which bears against the bottom of the rail above the space between the two 5 faces which bear upon the bar.

2. The combination with a railroad rail, and a stationary part of a road bed, of an anticreeper comprising an element adapted to engage the rail, and a spring wedge inserted 10 between the rail and the first named element and sprung from a normal condition and clamping the anticreeper to the rail in tending to resume said normal condition, said wedge having two bearing faces facing 15 in the same direction and spaced laterally from each other and a bearing face facing in the reverse direction and extending at an angle to the two first named faces and tending to move in a direction away from 20 the space between the two first named faces as the spring wedge tends to resume said normal condition, and said anticreeper being adapted to engage said stationary part.
- 25 3. The combination with a railroad rail having a base, and a stationary part of a road bed, of an anticreeper comprising a bar extending beneath the rail and provided with means to engage the top of the rail 30 base on each side thereof, and a spring wedge inserted between the rail and the first named element and sprung from a normal condition and clamping the anticreeper to the rail in tending to resume said normal 35 condition, said wedge having three separate bearing faces two of which face one direction and are spaced apart transversely of the rail and bear upon the bar and the other of which extends at an angle to the two 40 faces bearing upon the bar and bears against the bottom of the rail above the space between the two faces which bear upon the bar, and said anticreeper being adapted to engage said stationary part.

4. The combination with a railroad rail 45 having a base, and a stationary part of a road bed, of an anticreeper comprising a bar extending beneath the rail and provided with means to engage the top of the rail base on each side thereof, and a stop part 50 adapted to engage said stationary part and having a wedge shaped rearward extension located between the bottom of the rail and the top of the bar, said extension being formed of spring metal, concavo-convex in 55 cross section and having two separate faces bearing upon the bar and a face bearing against the bottom of the rail above the space between said separate faces, and said extension being sprung from a normal condition 60 and forcing parts of the anticreeper against the rail in tending to resume said normal condition.

5. The combination with a railroad rail, and a stationary part of a road bed, of an 65 anticreeper comprising an element adapted to engage the rail, and a wedge element inserted between the first named element and the rail, one element of the anticreeper being formed of spring metal and sprung 70 from a normal condition and forcing parts of the anticreeper against the rail in tending to resume said normal condition, said wedge element having spaced stop projections extending from the respective sides 75 thereof and arranged in staggered relation to each other and adapted to prevent movement of the first named element from different positions toward the small end of the wedge, and one of said elements being 80 adapted to engage said stationary part.

In testimony whereof we affix our signatures in the presence of two witnesses.
